CLAIM

The ornamental design of combined fountain brush
applicator bottle and cap therefor, as shown and de-
scribed.

DESCRIPTION

FIG. 1 is an exploded perspective view of a combined
fountain brush applicator bottle and cap therefor showing
our new design in inverted position;
FIG. 2 is a top plan view with the cap removed;
FIG. 3 is a front elevational view thereof;
FIG. 4 is a side elevational view thereof;
FIG. 5 is a bottom plan view;
FIG. 6 is a front elevational view with the cap in place;
and,
FIG. 7 is a top plan view thereof.
